REFRIGERATOR SHELF STRUCTURE

Norman W. Schmidt, Dayton, Ohio, assignor, by
mesne assignments, to General Motors Corpora-
tion, a corporation of Delaware

Application July 30, 1931, Serial No. 554,057

2 Claims. (Cl. 211—153)

This invention relates to refrigerator shelf structure, and more particularly to means for conserving useful space within a refrigerator cabinet.

5 One of the problems in designing a refrigerator cabinet has been to provide a proper space for the storing of tall articles therein. These tall articles are ordinarily few in number and usually consist of bottles. If the shelving is spaced wide enough to accommodate these tall articles, much useful space is lost because the majority of the articles stored within the refrigerator are relatively small in height compared to the tall articles, and many cannot be stacked and placed one on 10 top of the other.

Accordingly, the objects of my invention include the provision of means for utilizing the space within a refrigerator cabinet to provide additional shelf area in a refrigerator cabinet to 15 increase the amount of provisions which may be stored therein, and to provide means for storing tall articles such as bottles without reducing the number of shelves, without having a large distance between the shelf on which the tall articles 20 are stored and the shelf immediately above, without altering the desirable spacing of the shelves 25 and without occupying useful shelf area.

Further objects and advantages of the present invention will be apparent from the following description, reference being had to the accompanying drawing, wherein a preferred form of the present invention is clearly shown.

In the drawing:

Fig. 1 is a front view of a refrigerator cabinet embodying one form of the invention;

Fig. 2 is a plan view of a refrigerator shelf shown in Fig. 1, and

Fig. 3 is a perspective view of a refrigerator shelf embodying a form of the invention.

40 For the purpose of illustration, I have shown my invention as applied to a mechanically cooled refrigerator cabinet 20 having a machinery compartment 21 in its lower portion and a food storage compartment 22 in its upper portion. The food storage compartment is preferably cooled by a cooling unit 23 situated in an upper corner 45 of the compartment. Shelves 24, 25, and 26 are suitably spaced in a vertical direction within the compartment for providing a place whereon to lay and store provisions. These shelves are so closely spaced that tall articles, such as tall bottles, cannot be stored in an upright position thereon. These shelves are formed of a rectangular wire frame 27 upon which transverse cross bars 28, 50 preferably of wire, are provided. These cross

bars 28 are suitably spaced across the rectangular frame 27 and have their ends welded to the front and rear portions of the frame 27.

According to the present invention, I have provided a sub-shelf 30 for supporting the tall articles in a horizontal position. This sub-shelf 30 is preferably removable and constructed so that it may be suspended from one of the shelves in the cabinet and readily removed. In this way none of the useful shelf space will be taken and the space within the food storage compartment will be conserved. This sub-shelf comprises a pair of U-shaped wire members 31 and 32, of which the front U-shaped member has its upper ends turned forward in the form of hooks which 15 hook over the front edge of the rectangular wire frame member 27 of the shelf 26. The rear U-shaped member has its upper ends turned outwardly and laterally of the sub-shelf. The hook 34 at the left side of the rear U-shaped member 20 32 is of a relatively small width and hooks over one of the cross bars 28 of the shelf 26. A second hook 35 of the rear U-shaped member also extends outwardly and is supported upon another 25 of the cross bars 28. This hook, however, is 30 made wider than the hook 34 so that this width 35 may take care of any variation in the spacing of the cross bars 28. Preferably this hook is very nearly as wide as the space of the cross bar so that it may fit any shelf with any spacing of the cross bars.

Connecting the bottom portions of the front and rear U-shaped wire members 31 and 32 are the connecting bars 33 which extend longitudinally of the sub-shelf in spaced relation providing a supporting surface for the sub-shelf. These connecting bars 33 have their ends attached, preferably by welding or other suitable means to the front and rear U-shaped wire members 31 and 32.

40 Wire bars also extend around the sides of the sub-shelf for preventing the articles stored thereon from falling off. The wire bars 36 connect the sides of the front and rear U-shaped frame members 31 and 32 for providing a guard 45 upon the sides of the sub-shelf, while the bars 37 connect the sides of the rear frame member 32 for providing a rear guard for the sub-shelf and for preventing articles from falling off the rear portion of the sub-shelf. The front portion of the sub-shelf is, however, left open so that articles may be inserted upon the sub-shelf from this end.

50 55 With this sub-shelf tall articles may be placed thereon in a horizontal position. In Figs. 1 and 2,

the tall bottles 38 are shown stored upon the sub-shelf 30 in horizontal position. Since the portion of the food storage compartment immediately beneath each of the shelves is seldom occupied by provisions, the storage of tall articles there does not take any of the useful space of the food storage compartment and yet provides a space for the storage of tall articles which would otherwise require that a wide spacing of one of the shelves be provided. While primarily intended for tall articles, others may be stored upon the sub-shelf if desired. In this manner the space within the food storage compartment is conserved and yet a space is provided for tall articles.

15 While the sub-shelf has been described as made of wire, other materials such as pressed steel or even wood may be used. Other forms of supporting the sub-shelf may also be used.

20 While the form of embodiment of the invention as herein disclosed, constitutes a preferred form, it is to be understood that other forms might be adopted, all coming within the scope of the claims which follow.

25 What is claimed is as follows:

1. A refrigerator sub-shelf for supporting tall articles in a horizontal position including a rec-

tangular supporting member providing a supporting surface for articles, and means extending upwardly at the front and rear portions of said supporting member, said means having hooks at the upper ends, the hooks at the one end extending longitudinally of the supporting member, the hooks at the other end extending transversely of the supporting member, one of said last mentioned hooks being particularly wide for facilitating the connection of said hooks to a shelf 10 above the supporting surface.

2. A refrigerator sub-shelf for supporting tall articles in a horizontal position including a rectangular supporting member providing a supporting surface for articles, and means extending upwardly at the front and rear portions of said supporting member, said means having hooks at the upper ends, the hooks at one end extending longitudinally of the supporting member for detachably connecting to a transverse supporting member, the hooks at the other end extending transversely of the supporting member for detachably connecting to longitudinal supporting member.
